UNITED STATES PATENT OFFICE.

STEPHEN P. FLYNN, OF LOS ANGELES, CALIFORNIA.

TOBACCO-PIPE AND TUBE CLEANER.

No. 826,717.

Specification of Letters Patent.

Patented July 24, 1906.

Application filed July 20, 1905. Serial No. 270,561.

To all whom it may concern:

Be it known that I, STEPHEN P. FLYNN, a citizen of the United States, residing at Los Angeles, county of Los Angeles, State of California, have invented and discovered a new and useful Improvement in Tobacco-Pipe and Tube Cleaners; and I do hereby declare the following to be a full, clear, and exact description of the invention, such as will

enable others skilled in the art to which it appertains to make and use the same.

This invention relates to improvements in tobacco-pipe and tube cleaners; and the objects of my improvement are, first, to provide cleaners for pipes, tubes, flues, and the like economically constructed, and, second, to place upon the market cleaners that can be conveniently applied for the removal of noxious accumulations from pipes, tubes, flues, and the like.

The invention consists, essentially, in the construction, combination, and arrangement of the several parts, as will be hereinafter fully described in the specification, specifically pointed out in the claims, and shown upon the drawings appended hereto.

I attain these objects by the construction illustrated in the accompanying drawings, in which—

30 Figure 1 is a view in elevation of my improved tobacco-pipe cleaner, showing the rod protruded from the free end of the casing, the wire made a part of the casing spirally wound upon the protruding end of the rod in the direction shown by the arrow. Fig. 2 is a view in elevation of my improvement illustrated upon Fig. 1, the handle end of the rod extending from the handle end of the casing and the wire compressed between the free end of the 35 casing and the nut upon the free end of the rod, the wire wound upon the rod in the direction of the arrow. Fig. 3 is a view in elevation of my improvement shown upon Figs. 1 and 2 of the drawings, the wire wound upon 40 the rod in the direction shown by the arrow in the opposite direction from that shown upon Figs. 1 and 2, the handle end of the rod projecting from the handle end of the tube and the wire compressed between the free end 45 of the casing and the nut upon the free end of the rod. Fig. 4 is a longitudinal sectional view, on a large scale, of a modified form of my improved cleaner, part thereof broken away, the wire spirally wound upon the rod protruding from the end of the casing, the handle end of the rod screwed into the screw-threads

upon the inner surface of the handle end of the casing. Fig. 5 is a plan view of the blank from which the casing and the cleaning-wire integral therewith is manufactured, the wire 60 rolled in the usual way. Fig. 6 is a plan view of the blank shown upon Fig. 5 of the drawings, illustrating the cleaning-wire rolled in wire form and the body portion of the casing ready to be formed into a tube; and Fig. 7 is 65 a longitudinal sectional view of another modification of my improvement, part thereof broken away, showing the screw-threads upon the rod of greater length than the screw-threads in the forms shown in other figures of 70 the drawings.

Similar reference-numerals refer to like parts throughout the several views of the drawings.

The reference-numeral 1 denotes the casing 75 illustrated upon Figs. 1 and 2 of the drawings. 2 refers to the rod adapted to slide within the said casing. 3 indicates the knob, preferably interiorly screw-threaded and adapted to engage the screw-threads 4 upon the handle 80 end 2' of the rod 2. The said knob may, however, be fastened upon the rod 2 in any suitable manner.

The reference-numeral 6 refers to the pointed end of said rod, having screw-threads 7 85 thereon near the end thereof, as illustrated upon Figs. 4 and 7 of the drawings, and the numeral 8 denotes the screw-threaded nut secured near the end of the rod 2, adapted to engage the screw-threads 7 upon the wire end 90 of the rod 2, as shown upon Figs. 4 and 7 of the drawings.

In the end of the wire rolled portion formed from the blank 1' (illustrated upon Fig. 6 of the drawings) the hole or perforation 10, as 95 shown in the free end thereof, is adapted to be secured upon the pointed end 7 of the rod 2. After the perforated free end of the wire 11 has been seated upon the free end of the rod 2 the nut 8 is screwed down thereupon 100 and clamps the wire 11 against the shoulder 12, formed upon the rod.

The opposite end of the wire 11 is preferably made a part of the casing 1. The said wire may, however, be soldered to the casing 105 1 or secured thereto in any suitable manner. In place of the wire a fine cotton or silk thread may be used.

Upon Figs. 1 and 2 of the drawings the wire 11 is shown wound upon the rod 2, as indicated by the arrows shown thereon, and upon Fig. 3 the wire 11 is shown wound upon

the rod in the direction indicated by the arrow illustrated upon said figure.

In Figs. 1 and 2 of the drawings the wire 11 is shown wound in the opposite direction from that illustrated upon Fig. 3 of the drawings. The handle end 2' (in the last-mentioned figure the rod 2) is illustrated drawn farther through the casing 1 than in Fig. 2, and the loose wire 11 is clamped between the outer end of the casing 1 and the inner face of the nut 8 there compressed in somewhat spherical form larger than the end of the casing 1 and the nut 8, and in this position it is adapted to cut and remove nicotin and other objectionable accumulations in tobacco-pipes or tubes and noxious accretions in flues of various forms by pulling the said spherical form through pipes, tubes, and flues while in that shape.

The operation of my invention will readily appear from the foregoing description when taken in connection with the drawings appended hereto and made a part of the specification and claims, and further description of the manner of operating my improvement is deemed unnecessary.

It is obvious that many variations and changes in the detail of construction and arrangement of my invention would readily suggest themselves to persons skilled in the art and still be within the spirit and scope of my improvement.

Having described my invention, what I claim, and desire to secure by Letters Patent, is—

1. A tobacco-pipe, tube and flue cleaner, comprising a casing having a handle end portion, the opposite end of the casing provided with a wire having a perforation in the free end thereof, and a rod the end thereof adapted to be received within the said perforation and to be reciprocated within the casing.

2. A tobacco-pipe, tube and flue cleaner comprising a casing, having a wire secured thereto and provided with a perforation in

the end thereof, the said casing having screw-threads upon the inner surface of the handle end thereof and a rod pointed at one end and screw-threaded at the opposite end adapted to engage the screw-threads upon the handle end of the casing.

3. A cleaner comprising a casing having a wire made integral therewith the said wire provided with a perforation in the free end thereof, the said casing provided with screw-threads upon the handle end thereof, adapted to engage screw-threads upon a handle end of the rod, the said rod provided with a shoulder near the pointed end to receive the perforation in the end of the wire.

4. A cleaner comprising a casing having a wire made integral therewith provided with a perforation in the free end thereof, a rod having a shoulder near the end thereof, said rod screw-threaded near the pointed end thereof, a screw-threaded nut adapted to clamp the perforated wire against the shoulder upon the rod.

5. A cleaner provided with a casing having a wire perforated at one end, the opposite end of the casing interiorly screw-threaded, a rod having a pointed end, adapted to slide within the casing, the casing screw-threaded near the handle end thereof, said screw-threads upon the rod adapted to engage the interior screw-threads upon the inner surface of the casing.

6. A cleaner comprising a casing, a wire secured to the casing at one end, a rod adapted to be reciprocated within the casing, said rod provided with a pointed end and a shoulder near said end, and means for securing the wire to the rod.

In testimony whereof I have signed my name to this specification in the presence of two subscribing witnesses.

STEPHEN P. FLYNN.
